Patented Aug. 19, 1919.

FIG. 3

FIG. 1

FIG. 2

Inventor
Charles P. Beach,
By his Attorney,
Emery, Roos, Jaeney & Harvey.

UNITED STATES PATENT OFFICE.

CHARLES P. BEACH, OF LITTLETON, NEW HAMPSHIRE.

GEAR-REMOVER.

1,313,511.

Specification of Letters Patent. Patented Aug. 19, 1919.

Application filed July 26, 1917. Serial No. 182,847.

To all whom it may concern:

Be it known that I, CHARLES P. BEACH, a citizen of the United States of America, residing in the town of Littleton, in the 5 county of Grafton and State of New Hampshire, have invented an Improvement in Gear-Removers, of which the following is a specification.

My present invention relates to gear removers; and has for its object, to provide such a device of rugged and simple construction which may be rapidly put in place, and which, after it is adjusted in position, is locked there. It further has for its object 10 the provision of means by which the jaws which embrace the gear to be removed are by the relative motion of the gear and shaft in the operation of the device more closely approximated to the gear, so that when the 15 gear and shaft move relatively, the jaws do not slip away, but are maintained in position. Another object of the invention is to arrange such a remover as I have above outlined so that it may employ either two jaws 20 or a greater number, as may be desired. In general three will be sufficient, even for the largest sizes, and this is the best number, as there is then no tendency to rock, since three points determine the transverse plane of the 25 device when applied. There are, however, conditions in which only two jaws can conveniently be employed.

To accomplish the ends pointed out, I provide a plurality of swinging arms for 30 engaging the gear, which are bell-crank levers, and these are hinged to a hub; concentric with the hub is a sliding sleeve which is provided with a collar having recesses or a recess which engages the inner 35 ends of the bell-crank levers, so that as the hub is moved away from the hub, pressure is applied to open the bell-crank levers and when the hub is approximated to the 40 hub, the outer ends of the levers are pressed toward the shaft and gear. Through the 45 axis of the sliding sleeve passes a screw, having a coned end, which is to be applied to the shaft; a locking device is provided also, so that when the sleeve and hub are in 50 the desired relative position, they are locked together, thus causing the ends of the bell-crank levers to be held firmly in engagement with the gear.

The accompanying drawings show an embodiment of my invention.

55

Figure 1 is a side elevation of the gear remover complete.

55

Fig. 2 is a similar view, partly in vertical section, of the parts shown in Fig. 1.

60

Fig. 3 is a plan.

60

A base or supporting member, such as the hub A is provided with the lugs marked A¹ to A⁴ respectively. The lugs A² and A⁴ are diametrically opposite; and in the device here illustrated each of them carries a gripping member, preferably in the form of a bell-crank lever B swinging upon a pin B¹. The lugs A¹ and A³ are arranged 120° apart and at the same angle with either one or the other of the lugs A², A⁴. By this arrangement, additional bell-crank levers may be disposed in these lugs and the one in the lug A⁴ may be removed; the gear remover is then provided with three arms, and for the larger gears this is the preferred 75 arrangement. In many cases, however, particularly in machinery which is assembled and where it is desired to remove a gear from the shaft or to apply the remover without taking down the engine or other machine, it is only possible to find passageways for two of the levers. Each of the bell-crank levers is provided with a short arm B², disposed substantially at a right angle to the longer arm.

85

C is a member longitudinally movable with respect to the base A and the operating member D subsequently to be described, and may comprise a sliding sleeve, which is provided with the collar C², preferably formed integral therewith; the collar has a groove, or a suitable number of recesses as may be desired, C¹, in which are disposed the short arms B² of the bellcrank levers, the lower sides of which are slightly curved so that the lower ends of the levers may move freely toward and away from the axis of the instrument as their short arms are raised and lowered by the sleeve C. It is obvious that as the sleeve C is moved downward in Figs. 1 and 2, pressure will be applied to the upper sides of the short arms of the levers and they will be spread apart at their lower ends as shown in dotted lines in Fig. 2; and when the sleeve C is drawn up, the arms 105 will be approximated to the gear or shaft.

100

105

- D is the operating means, comprising preferably a single operating member herein shown, by way of example, as consisting of a screw by which power is applied to the end 5 of the shaft, to force off the gear. It is provided with a coned end D² to fit the center mark in the shaft end, and a squared end D¹ to which a suitable handle or wrench may be applied.
- 10 E is the handle of the locking device, which is threaded upon and secured by the pin e to a bolt E¹; in a recess in the collar A⁵ forming part of the hub A are disposed nuts E² E³, respectively threaded right and left hand upon the bolt E¹. When the handle is turned to release the pressure of the nuts upon the sleeve c, the latter is free to move; but when the handle is depressed, as shown in Fig. 1, the sleeve and the hub are 15 locked together as the nuts are forced together and against the outer surface of the sleeve, and move under the power of the screw D as an integer. Obviously other forms of locking device may be employed.
- 20 25 The operation of the gear-remover is as follows: When it is to be applied to a gear, such as the gear F shown in dotted lines in Fig. 2, sleeve c is moved down, pressure is thereby applied to the upper sides of the short arms B² of the levers B so that the 30 longer arms are spread into the position shown in dotted lines; the hooked ends b b of the levers are then adjusted below the gear, the sleeve c is drawn up until the hooked 35 ends b of the levers pass under the gear, taking care to center the cone D² of the screw upon the shaft G, the screw being of course adjusted to the correct distance from the hooks b; the handle E is then depressed, 40 locking the hub and sleeve together, whereupon rotation of the screw D will apply endwise pressure to the shaft relative to the gear F, and the latter will be readily removed.
- 45 50 55 The effect of the described operation is to furnish always a horizontal component of the pressure applied by the screw, in such a direction as to approximate the levers to the shaft or gear so that by no possibility can they slip away from the gear. This has sometimes been effected by some separate arrangement, such as a ring to slip over the arms of the gear-remover, or the like, but these are dispensed with by the arrangement 60 65 which I have illustrated.
- The device has obvious advantages, being of rugged construction and simple to operate, both in adjusting it into position and in applying the operating pressure. Of course it may be applied equally well to remove hubs or pulleys, propellers, or the like.
- I claim as my invention:
1. A gear remover comprising a supporting member, a plurality of movable gripping members attached to said supporting

member, an operating member for said gear remover associated with said gripping members, and means associated with said gripping members and with said operating member for causing said gripping members to approach each other during the action of said operating member.

2. A gear remover comprising a base, a plurality of movable gripping members supported by said base, operating means for 75 said gear remover, and means associated with said operating means and actuated by the same for causing said gripping members to approach each other.

3. A gear remover comprising a hub carrying levers, a sleeve acting upon the levers by movement relative to the hub to approximate the levers to a gear, means for locking the sleeve and hub together, and means for imparting movement to the device in a direction to remove the gear.

4. A gear remover comprising a base, a plurality of movable gripping members pivoted to said base, an operating member for said gear remover associated with said gripping members, and means associated with said gripping members and with said operating member for pivotally moving said gripping members to cause the same to approach each other during the action of said 95 operating member.

5. A gear remover comprising a base, a plurality of movable gripping members pivoted to said base, operating means for said gear remover, and means associated with 100 said operating means and actuated by the same for causing said gripping members to pivotally approach each other.

6. A gear remover comprising a hub, swinging levers carried by the hub, a part moving 105 in the hub and engaging the ends of the levers so that its motion relative to the hub in one direction causes the free ends of the levers to approach each other and in the other direction causes them to separate, 110 means for locking the hub and the part together; and a screw the end of which moves toward and away from the free ends of the levers and conversely relatively to the hub.

7. In a gear remover, a hub, bell crank 115 levers carried by the hub, a sleeve concentric with the hub and sliding therein, the sleeve engaging the ends of the levers and by its motion relative to the hub opening and closing their free ends, and a locking device for 120 securing the sleeve and hub together; with a screw the end of which moves relative to the sleeve and hub toward and away from the free ends of the levers.

8. A gear remover comprising a base, a 125 plurality of movable gripping members attached to said base, a movable member associated with said base and capable of movement longitudinally of the same, operating means associated with said movable member 130

and capable of movement longitudinally of the same, and means associated with said movable member for causing said gripping members to approach each other by the action of 5 said operating means.

9. A gear remover comprising a supporting member, a plurality of movable gripping members pivoted to said supporting member, a movable member associated with said 10 base and capable of movement longitudinally of said base, operating means associated with said movable member and capable of movement longitudinally of the same, and means associated with said movable member 15 for causing said gripping members to be pivotally moved to approach each other by the action of said operating means.
10. A gear remover comprising a base, a plurality of movable gripping members supported by said base, operating means for 20 said gear remover, and means associated with said gripping members and with said operating means and actuated by the latter for causing said gripping members to approach each other to grip the work with a 25 force increasing as the force exerted on the work by the gear remover increases.

11. A device of the character described, comprising, in combination, a supporting member, a plurality of movable gripping members supported by said supporting member, and operating means for said gear remover acting to cause said gripping members to approach each other to grip the work when said gear remover is brought into operative relation with the work. 30 35

12. A gear remover comprising a base, a plurality of gripping members each pivoted intermediate its ends to said base, a movable member associated with said base and with 40 said gripping members and adapted to engage the non-work-gripping ends of said pivoted gripping members, and operating means associated with said gripping members and with said movable member and acting to cause said movable member to actuate said gripping members to cause the latter to approach each other to grip the work at the same time that the operating means is brought to bear against the work. 45 50

In testimony whereof I have signed my name to this specification this 24th day of July, 1917.

CHARLES P. BEACH
